UNITED STATES PATENT OFFICE

96,742

DESIGN FOR A PICTURE FRAME

Abraham Golden, Chicago, Ill.

Application June 3, 1935, Serial No. 57,109

Term of patent 3½ years

To all whom it may concern:

Be it known that I, Abraham Golden, a citizen of the United States, residing at Chicago, Cook County, and State of Illinois, have invented a new, original, and ornamental Design for a Picture Frame, of which the following is a specification, reference being had to the accompanying drawing, forming part thereof.

Fig. 1 is a front elevation of a picture frame showing my new design, and

Fig. 2 is a detail cross-section taken on the line 2—2 of Fig. 1.

In the drawing, the surface ornamentation, fragmentarily shown on the two parallel strips, is repeated throughout the same.

I claim:

The ornamental design for a picture frame, as shown and described.

ABRAHAM GOLDEN.
